UNITED STATES PATENT OFFICE.

AUGUST KOENIG, OF LOWELL, MASSACHUSETTS, ASSIGNOR TO THE LAMSON COMPANY, OF BOSTON, MASSACHUSETTS, A CORPORATION OF NEW JERSEY.

PNEUMATIC-CARRIER-DECELERATING APPARATUS.

1,256,024.

Specification of Letters Patent. Patented Feb. 12, 1918.

Application filed January 6, 1917. Serial No. 140,930.

To all whom it may concern:

Be it known that I, AUGUST KOENIG, a citizen of the United States, residing at Lowell, in the county of Middlesex and State of Massachusetts, have invented certain new and useful Improvements in Pneumatic-Carrier-Decelerating Apparatus, of which the following is a specification.

This invention relates to pneumatic despatch tube apparatus of the pressure type and more especially to an improved means for effecting the deceleration of fluid pressure propelled carriers, preferably just prior to the delivery of the same. It is usually extremely desirable to effect a quiet and substantially momentumless discharge of carriers at the station for which they are intended and, especially in despatch systems in which the carrier is propelled by compressed air, it has been found difficult to deprive carriers, being delivered, of their momentum, relieving them of the pressure of the air therebehind and depositing them substantially without shock or noise in or upon a suitable repository, and this without interference with certainty of operation.

Indeed, to assure a positive delivery of each carrier, regardless of the varying pressure conditions in the system, it has been common to sacrifice quietness to a certain extent; the carriers being permitted to emerge from the delivery terminal with some force.

One of the principal objects of the present invention, therefore, is to effect the desired certainty of delivery of carriers while substantially eliminating noise and jar at their discharge, wear and tear on the apparatus, and like accompanying objectionable incidents, hitherto undesirably common.

I have also aimed to accomplish the desired results in the simplest possible manner, and preferably without the provision of any moving parts, other than the carrier *per se*. These and other objects of the invention will be hereinafter referred to and the novel combinations of means and elements whereby said objects may be attained, will be more particularly pointed out in the appended 50 claims.

In the accompanying drawing which forms a part hereof and in which like reference characters designate like parts in the respective views, I have exemplified a preferred form of the device; but as I am aware

of various changes and modifications which may be made herein without departing from the spirit of the invention, I desire to be limited only by the scope of the claims.

Referring to the drawing:

Figure 1 is a side elevation of an improved carrier delivery apparatus.

Fig. 2 is a detail side elevation of an air outlet bend which constitutes a part of said apparatus; and

Fig. 3 is a detail section taken on line III-III of Fig. 2.

As the invention more particularly concerns pressure pneumatic despatch tube apparatus, the sections of transit tubing 1, shown in Figs. 1 and 2, have the carrier propelling current of air traveling therethrough in the direction of the arrows; and the carrier 2 will emerge from said tube 1 into what I term an air outlet bend, 3. As best shown in Fig. 2, this bend may be one of about 90°, and the interior diameter of the carrier conducting conduit provided therein is caused to increase gradually from the entrance end of the bend around to substantially midway of the length thereof, and thereafter to gradually decrease until the diameter of the transit tubing is again approximated; this being done to permit of a free passage of the carriers around the bend, in spite of the short radius of curvature of the latter.

The carrier upon its emergence from said bend preferably enters a short downwardly directed tube section 4, which in turn delivers to a chute 5. This latter again preferably has a very short radius of curvature, as compared to that of chutes or shelves commonly used in similar positions in pneumatic despatch tube apparatus; and this chute furthermore does not normally serve to retain carriers in place therein, but acts to direct said carriers toward a trough-like repository 6, which may conveniently be made a part of the desk 7 at which the operator or clerk is stationed.

The carrier delivering end 5' of this chute is also preferably up-turned so that the chute as a whole provides means for rotating the carrier about its center of gravity, during its transit through the chute, through somewhat more than 90°.

I particularly desire to call attention to the abruptness of curvature of both the outlet bend 3 and this delivery chute; and the

reasons for this will be hereinafter pointed out.

The bend 3 is preferably made in two parts, which may be connected together by bolts 8, as shown in Figs. 2 and 3; and the principal peculiarity of this bend resides in the fact that openings 9 are provided upon the respective sides thereof in such position as to be practically directly in the path of the air current entering the bend from the tube 1; while further the rib 3' which serves to guide the carriers during their passage past the openings 9, is so formed that the carrier engaging surface 10 thereof is reduced, as shown in Fig. 3, to a minimum, it being best made just sufficiently wide to avoid the presentation of a sharp edge which would tend to cut into the felt, leather or rubber heads of the carrier.

In order to give the blade-like rib proper thickness, in spite of this provision of a very narrow carrier-guiding surface 10, said rib may be tapered or flared outwardly, as indicated in Fig. 3, but it is preferable that such flaring or thickening of said rib toward its outer edge be not excessive. The reason for this construction is that, as a result of experimentation, I have found that if any material width of surface (corresponding to that designated 10, but materially wider) be presented to the air current which propels the carriers, such surface will act to deflect quite a considerable part of said air current downwardly toward the tube 4 and thereby prevent the carrier from being entirely relieved from the propulsive effort of the air therebehind. In order to get the best results, in so far as a quiet delivery of carriers is concerned, it is essential that this pressure of air behind the carrier be as completely removed as possible, prior to the entrance of the carrier into the tube 4, or any equivalent downwardly directed delivery element.

By thus reducing the carrier guiding surface 10, to a minimum compatible with the avoidance of undue wear and tear upon the carriers passing along and guided by such surface, I substantially eliminate all tendency for the air current to follow the carrier and cause said air current to pass out freely through the openings 9, as indicated by the arrows directed outwardly from said openings in Fig. 1.

The operation of the device as a whole is as follows: Carriers propelled by compressed air therebehind, pass out of the transit tube 1 into the turn 3, and are thrust against the narrow surface 10 by their momentum, coupled with the air pressure therebehind, until the openings 9 have been exposed to the air current by the travel of the carrier around said bend, and by reason of the sharpness of the bend and the friction

consequently engendered between the heads of the carrier and said narrow surface of contact 10, the momentum of said carrier is substantially absorbed. By the time that the carrier has completely cleared the openings 9, owing to the disposition of these openings directly in the path of the air current, said carrier will be practically entirely relieved from any propulsive effort of the air, and the air current will pass with the utmost freedom out through said openings. Thereafter, as the carrier falls through the short tube section 4, it will of course tend to regain some momentum by reason of the action of gravity, but such regained momentum will be practically completely absorbed or neutralized during the passage of the carrier through the short and abruptly turned chute 5; with the result that said carrier simply falls lightly and easily clear of the chute and into the repository 6.

I may add that it was really surprising to observe during the course of experimentation upon apparatus of this description, how the air current does tend to follow around curved surfaces of any material width lying in its path, in spite of the provision of openings upon either side of said surface through which, one would be convinced, the air should certainly find sufficient opportunity to freely expand.

Having thus described my invention, what I claim is:

1. In carrier decelerating apparatus for pneumatic despatch tube systems, the combination of a transit tube through which carriers are propelled by the pressure of compressed air therebehind, with an abruptly curved air-outlet turn casing into which said carriers pass from said tube, said casing comprising carrier guiding means for rotating carriers in course of transit therepast about their centers of gravity and the parts of said guiding means which actually engage and guide the carriers, being reduced substantially to an edge, said guiding means being in cross-section substantially that of a blade, the turn in said casing being further directly in the path of said air current and the space therein through which the carriers pass, being in unrestricted communication, about said blade-like guiding means, with the outer air.

2. Pneumatic despatch tube apparatus comprising a tube through which carriers are despatched by compressed air, a carrier decelerating bend connected to said tube to receive carriers therefrom, said bend having on its outer side and in the path of the air current emerging from said tube, a single narrow arcuate carrier-guiding rib and air outlets upon both sides of the latter.

3. Pneumatic despatch tube apparatus comprising a tube through which carriers are despatched by compressed air, a carrier

decelerating bend connected to said tube to receive carriers therefrom, said bend having on its outer side and in the path of the air current emerging from said tube, a narrow row arcuate carrier-guiding rib and air outlets upon both sides of the latter, said bend being made of two curved trough-shaped parts and having means to fasten said parts together, the plane in which said

parts join being substantially that of said rib.

In testimony whereof I have affixed my signature, in the presence of two witnesses.

AUGUST KOENIG.
